UNITED STATES PATENT OFFICE.

DARIUS WILCOX, OF MECHANICSBURG, PENNSYLVANIA.

FIFTH-WHEEL.

SPECIFICATION forming part of Letters Patent No. 603,070, dated April 26, 1898.

Application filed July 9, 1897. Serial No. 644,000. (No model.)

To all whom it may concern:

Be it known that I, DARIUS WILCOX, a citizen of the United States, residing at Mechanicsburg, in the county of Cumberland and State of Pennsylvania, have invented certain new and useful Improvements in Fifth-Wheels; and I do hereby declare the following to be a full, clear, and exact description of the invention, such as will enable others skilled in the art to which it appertains to make and use the same.

The invention relates to turn-short fifth-wheels; and it consists of certain details of structure which will be fully hereinafter explained.

The objects of the invention are to so construct a wheel that it will be very strong, compact, and substantial, with the minimum amount of material, and that enables a vehicle to be turned easily and in a very short space and enables the body thereof to be set low down and not strike the reach.

In the accompanying drawings, forming a part of this specification, Figure 1 is a perspective view of the wheel applied to the axle-bed and head-block. Fig. 2 is a longitudinal central section.

Like letters indicate corresponding parts in both views.

30 A is the head-block, which is of any usual or desired form.

B is the axle-bed, and C is the reach.

D is the bottom wheel or half-circle, and E is the top wheel or circle.

35 The head-block A is provided on the under side with the usual head-block iron, and the springs and body of the vehicle are secured to the head-block in the customary manner, and the construction is such that the body 40 with this wheel is set low down.

F is the reach-iron on the under side of the reach, and it extends forward to and underneath the head-block A, and it is provided with a frusto-conical boss or projection f, depending therefrom and which fits into the socket or aperture through the double brace, as will be presently described.

45 G is the double brace, and it extends from the under side of the reach C toward its front 50 end to the axle-bed B and is secured thereto by suitable clips f' f'.

A foot or brace H on the under side of the

reach and double brace is bolted to the reach by bolts h' h' h', and the reach-iron F and foot or brace H have pivoted bearings on the bolt 55 h'', which passes through the reach, reach-iron, double brace, and foot or brace H, as well shown in Fig. 2. The double brace F has inverted frusto-conical bearings which correspond with the frusto-conical depending 60 cone f on the reach-iron and the upwardly-projecting frusto-conical boss or bearing f' on the foot or brace H, and balls may be used between the cones just described, thus furnishing ball-bearings on which the wheel may 65 easily turn. Instead of having the frusto-conical bosses and the reach-iron and the brace or foot H, these cones may be on the double brace and corresponding bearings be provided in the reach-iron and the brace or 70 foot H, which would be simply a reversal of the construction, as will be readily apparent.

The under wheel or half-circle D has helical braces d on its inner ends, which extend forward to the rear of the axle-bed and are secured thereto by bolts passed through the same or by clips or in any other suitable manner.

The top wheel E is circular in front and approximately heart-shaped in the rear, and the 80 free ends of the same are bolted to the reach at each side, as shown at a a.

Embracing both wheels in front is a yoke which straddles the lower members D E of the wheel, and it has a spring on the under side 85 forming an antirattling device, as in patent of D. Wilcox, dated July 17, 1894, No. 523,252.

The balls in the races formed by the cones in the socket or aperture through the center of the double brace and on the reach-iron F 90 and foot or brace H enable the wheel to be turned very easily; but it will be apparent that it would operate well without the use of balls. By means of the bolt h'' and the nut thereon the wear is easily and conveniently 95 taken up without disassembling the parts.

It will be noticed that the foot or brace H is extended forward and secured to the reach at that point by the front bolt h', and this construction does away with the center bolt 100 h'', if preferred, and makes a very strong construction. It will also be seen that the lower wheel is held to the axle-bed not only by vertical bolts, but also by bolts transversely of

the axle-bed, which secure the helical braces on the end of the wheel firmly thereto.

Minor changes in the details of the structure may be made within the scope of the invention without departing from the spirit or sacrificing any of the advantages thereof.

Having thus fully described the invention, so that any person familiar with the art may make, construct, and use the same, what I claim as new, and desire to secure by Letters Patent, is—

1. In fifth-wheels, the lower half-circle provided with helical braces at its ends, secured to the axle-bed by transverse bolts in addition to the usual vertical fastenings, substantially as set forth.

2. In fifth-wheels, the lower half-circle provided with helical braces at its ends, secured to the axle-bed by transverse bolts, in addition to the usual vertical fastenings, and the top circle or wheel formed approximately heart-shaped in the rear, and having its free ends bolted to the reach at each side thereof, substantially as set forth.

25 3. In fifth-wheels, the reach-iron provided with a frusto-conical, depending boss and a lower curved brace or foot with an upwardly-projecting frusto-conical boss, in combination with a double brace, arranged between the reach-iron and foot and provided with corresponding cone-recesses, having its arms downwardly bent, and secured to the axle-bed, by means of clips, substantially as set forth.

4. In fifth-wheels, the reach-iron provided 35 with a frusto-conical depending boss, and a lower curved brace or foot, extending forward toward the rear of the axle-bed, secured to the reach in front, and provided with a double brace arranged between the reach-iron and

foot or lower brace, and furnished with cone-seats, the two arms of said double brace secured to the axle-bed, and a bolt, forming a pivot and taking up the wear, passed through the reach, reach-iron, double brace and foot and having an adjusting-nut on its lower end, substantially as set forth.

5. In a fifth-wheel, the reach-iron provided with a frusto-conical, depending boss, and a lower curved brace or foot with an upwardly-projecting frusto-conical boss, in combination with a double brace, arranged between the reach-iron and foot and provided with cone-seats, balls in the races formed by the cones and recesses and having its two ends secured to the axle-bed by means of clips, substantially as set forth.

6. A fifth-wheel having its lower half-circle with forwardly-curved braces at its ends, secured to the rear of the axle-bed by transverse bolts, a top circle, approximately heart-shaped in the rear, and with its free ends secured on each side of the reach, a yoke or clip connecting the two members of the wheel in front, a reach-iron with a depending, frusto-conical boss; a lower brace or foot with an upwardly-projecting frusto-conical boss and a double brace with cone-recesses to fit the bosses on the reach-iron and lower brace or foot, said double brace having its two downwardly-curved arms secured by clips to the axle-bed, substantially as set forth.

In testimony whereof I affix my signature in presence of two witnesses.

DARIUS WILCOX.
